US0D1073572S

(12) **United States Design Patent** (10) **Patent No.:** **US D1,073,572 S**
(45) **Date of Patent:** **** May 6, 2025**

(54) **FUEL SYSTEM ENCLOSURE**

(71) Applicant: **Agility Fuel Systems LLC**, Costa Mesa, CA (US)

(72) Inventors: **Taylor Robinson**, Happy Valley-Goose Bay (CA); **Momchil Yordanov**, Kelowna (CA); **Aaron Heffelfinger**, Kelowna (CA)

(73) Assignee: **Agility Fuel Systems LLC**, Costa Mesa, CA (US)

(**) Term: **15 Years**

(21) Appl. No.: **29/850,675**

(22) Filed: **Aug. 22, 2022**

(51) **LOC (15) Cl.** **12-16**

(52) **U.S. Cl.**

USPC **D12/218**

(58) **Field of Classification Search**

(57) **CLAIM**

The ornamental design for a fuel system enclosure as shown and described.

DESCRIPTION

FIG. 1 is a rear right perspective view of a fuel system enclosure;

FIG. 2 is a right front perspective view thereof;

FIG. 3 is a rear left perspective view thereof;

FIG. 4 is a front view thereof;

FIG. 5 is a rear view thereof;

FIG. 6 is a right view thereof;

FIG. 7 is a left view thereof;

FIG. 8 is a top view thereof;

FIG. 9 is a bottom view thereof;

FIG. 10 is a rear left perspective view of the claimed design applied to a different fuel system enclosure;

FIG. 11 is a right front perspective view thereof;

FIG. 12 is rear left perspective view thereof;

FIG. 13 is a front view thereof;

FIG. 14 is a rear view thereof;

FIG. 15 is a right view thereof;

FIG. 16 is a left view thereof;

FIG. 17 is a top view thereof; and,

FIG. 18 is a bottom view thereof.

Broken lines in FIGS. 1 and 10 illustrating a heavy duty vehicle illustrate environment which forms no part of the claim. All other broken lines illustrate unclaimed portions of a fuel system enclosure.

1 Claim, 16 Drawing Sheets
